UNITED STATES PATENT OFFICE.

JOHN H. HAWLEY, OF NEW YORK, N. Y., ASSIGNOR TO AMERICAN ENAMEL CO., A CORPORATION OF RHODE ISLAND.

DESIGN FOR A BUTTON.

45,003.

Specification for Design.

Patented Dec. 9, 1913.

Application filed September 24, 1913. Serial No. 791,660. Term of patent 3½ years.

To all whom it may concern:

Be it known that I, JOHN H. HAWLEY, a citizen of the United States, residing at No. 100 West Seventy-ninth street, in the borough of Manhattan, city, county, and State of New York, have invented a new, original, and ornamental Design for Buttons, of which the following is a specification, reference being had to the accompanying drawing, forming part thereof.

Figure 1 is a side elevation of a button

embodying my invention. Fig. 2 is an end elevation thereof. Fig. 3 is a top plan view thereof.

I claim:

The ornamental design for a button, substantially as shown.

JOHN H. HAWLEY.

Witnesses:

AXEL V. BEEKEN,
TERESA V. LYNCH.
